OXYGEN DISTRIBUTOR

Frank G. Manson, Dayton, Ohio

Application September 11, 1937, Serial No. 163,356

9 Claims. (Cl. 128—205)

(Granted under the act of March 3, 1883, as
amended April 30, 1928; 370 O. G. 757)

The invention described herein may be manufactured and used by or for the Government for governmental purposes, without the payment to me of any royalty thereon.

5 The invention relates to oxygen distributors and particularly to face mask oxygen distributor assemblies for supplying oxygen to airplane pilots at high altitudes.

The object of the invention is to provide a face 10 mask oxygen distributor assembly of novel and improved construction having advantages of use and operation over all other types of oxygen masks in that it permits normal unrestricted breathing and exhalation through the nose and 15 mouth with ample provision for vocal communication.

Other objects and advantages of the invention may be apparent from the following detailed description and from the accompanying drawings, 20 wherein:

Figure 1 is a front view of a face mask oxygen distributor assembly constructed in accordance with the invention;

Figure 2 is a side view;

25 Figure 3 is an enlarged detail view, in top plan, of the oxygen distributor.

Figure 4 is a view, in front elevation, of the oxygen distributor;

30 Figure 5 is a cross-section on line 5—5 of Fig. 4, and

Figure 6 is a cross-section on line 6—6 of Figure 5.

The mask used with the oxygen distributor is preferably of the type illustrated in the drawings 35 and consists of a face piece 10, chin piece 11 and strap 12. It is designed to fit snugly over the nose and mouth and under the chin of the wearer. The nose portion 13 forms a protuberance on the face of the mask above the mouth portion and 40 is completely open to the atmosphere at its under side 14 to permit breathing through the nose. The mouth portion of the mask is open to the atmosphere through a rectangular opening 15 to permit breathing through the mouth.

45 The oxygen distributor consists of upper and lower metal tubes 16 and 17 forming separate oxygen conduits; the lower tube being preferably straight and the upper tube arcuate as shown in Figure 4. The lower tube 17 has an open end 18 for connecting to a flexible oxygen supply tube and is closed at its opposite end 19. The end 20 of the upper tube 16 is soldered to the lower tube around an opening 21 in the latter spaced inwardly from the open end 18 of the tube. The 50 opposite end 22 of the upper tube is closed. Oxy-

gen outlet openings 23 are provided in the top side of the upper tube 16 and similar openings 24 in the under side of the lower tube 17. The oxygen outlet openings 23 and 24 are made at an angle to prevent direct flow of the oxygen against 5 the mask wearer's mouth and nose. A nose baffle plate 25 of sheet metal is attached to the upper tube 16 and a mouth baffle 26 plate of similar material is attached to the lower tube 17. The outer surfaces of the baffle plates may be covered with 10 leather. The mouth baffle plate 26 has an angularly bent portion 27 terminating in a right angularly disposed foot or flange 28. Soldered or otherwise secured to the tubes 16 and 17 on respectively opposite sides of the plate portion 27 are 15 flanged metal sheets or plates 29 and 30; the latter being at the ends 19 and 22 of the tubes. The side plates 29 and 30, together with the plate portion 27, serve as spacers and supports for maintaining the distributor in proper outwardly 20 spaced relation to the nose and mouth of the user; the feet or flanges of the plates being disposed as shown in Fig. 3 substantially in a common arc conforming to the curvature of the mask. Small 25 openings 31 are formed in each of the flanges for the reception of the attaching means.

The oxygen distributed is preferably attached to the mask by stitching 32, with the flange 28 of the mouth baffle plate 26 located immediately below the lower edge of the mask mouth opening 30 15 and with the upper edge of the nose baffle plate 25 extending up into the opening 14 of the mask nose 13. The side plates 29 and 30 are fastened to the mask at opposite sides of the opening 15 and occupy a mid position between 35 the nose opening 14 and the lower portion of the mouth opening 15 to provide open spaces at the upper and lower sides of the distributor. These open spaces, together with the open space between the upper and lower tubes 16 and 17, permit 40 substantially normal unrestricted breathing through the nose and mouth as well as vocal communication. The metal baffle plates around the mouth and nose cause the flow of oxygen from the oxygen outlet openings to be deflected up to 45 the mouth and directly under the nose and also prevent too rapid diffusion of the oxygen away from the user.

From the foregoing it will be apparent that the invention provides a means of supplying oxygen 50 at high altitudes to an airplane pilot in such a manner that a column of oxygen gas is maintained around the user's nose and mouth without interfering with normal unrestricted breathing. As normal breathing is permitted with this type 55

of distributor, means of vocal communication by radio is not prevented as is the case with all other types of oxygen mask assemblies where the pilot is required to have either a supply or an exhalation tube in his mouth. Fogging of the pilot's goggles and formation of ice around the distributor due to restricted exhalation is avoided in this device by the provision for unrestricted exhalation.

10 Having thus described the invention, what I claim is:

1. A face mask oxygen distributor assembly comprising a face mask having oral and nasal apertures open to the external atmosphere, and 5 an oxygen distributor attached exteriorly to the mask between the said oral and nasal apertures and having oxygen outlet openings baffled for deflecting the oxygen through the said apertures of the mask.

15 2. An oxygen distributor consisting of tubing having laterally adjacent branches one of which is adapted to fit in front of the mouth and the other under the nose of the user without closing the oral or nasal openings to the immediate outside atmosphere, said tubing having means for connecting to a source of oxygen supply and said branches having outlet openings for diffusion of the oxygen around the oral and nasal openings so that the oxygen and outside atmosphere may be 20 breathed through these openings and without interference with the user's speech, and baffles on the said branches of the tubing to prevent too rapid diffusion of the oxygen away from the user.

25 3. An oxygen distributor comprising tubing closed at one end and having the opposite end open for connecting to a flexible oxygen supply tube and having oxygen outlet openings at opposite sides thereof, means attached to the tubing and engageable with the head of the user for supporting the tubing in front of the mouth and under the nose of the user without closing the oral and nasal openings to the outside atmosphere, and baffle members on the tubing and inclined over the said oxygen outlet openings providing for separate and indirect baffled flow of oxygen to the nose and mouth.

30 4. An oxygen distributor comprising tubing having an open end for connecting to a source of oxygen supply and having oxygen outlet openings, 35 means for supporting the tubing in position above the mouth and under the nose of the user and spaced therefrom to permit normal unrestricted breathing with freedom of vocal communication, the said oxygen outlet openings of the tubing being 40 angularly disposed to prevent direct flow of the oxygen against the mouth and nose, and baffle members carried by the tubing and extending around the mouth and under the nose.

45 5. An oxygen distributor comprising tubing adapted to be connected with a source of oxygen supply and having oxygen outlet openings in relatively spaced relation along the upper and lower sides, means on the said tubing attachable to the person of the user to support the tubing in front of the mouth and under the nose of the user with-

5 out closing the oral and nasal openings to the outside atmosphere, and baffles mounted on the said tubing adjacent the said openings to cause the flow of oxygen therethrough to be deflected to the mouth and nose, said baffles being arranged to define a restricted and partially inclosed space in the vicinity of the user's nose and mouth for retarding the diffusion of the oxygen away from the user.

6. An oxygen distributor adapted to fit over the user's mouth and under the nose and comprising metal tubing open at one end for connection with a source of oxygen supply and closed at the opposite end and between the open and closed ends having separate upper and lower oxygen conduits, the upper conduit having oxygen outlet openings in its top side and the lower conduit having oxygen outlet openings in its bottom side, a nose baffle plate on the forward side of the upper conduit and extending upwardly and inwardly over the outlet openings in the said upper conduit, a mouth baffle plate on the forward side of the lower conduit and extending downwardly and inwardly under the outlet openings of the said lower conduits, and supporting plates secured to the said upper and lower conduits beyond the said baffle plates and extending rearwardly of the said conduits for supporting the latter in outwardly spaced relation to the mouth and nose of the user.

30 7. A face mask oxygen distributor assembly comprising a mask having oral and nasal apertures open to the external atmosphere, and an oxygen distributor on the outer side of the mask in spaced relation to the said apertures and having separate dispensing means for directing separate baffled flow of oxygen through the said apertures.

35 8. An oxygen distributor having, in combination, a feed tube provided with means for connection with a source of oxygen supply and with an outlet for the diffusion of the oxygen therefrom, means on the tube and engageable with the person of the user for supporting the tube with its outlet in the vicinity of the user's nose and mouth so that the external atmosphere as well as the oxygen may be breathed through the oral and nasal openings without interference with the user's speech, and baffles on the tube for preventing the too rapid diffusion of the oxygen away 45 from the said vicinity.

40 9. A device for supplying oxygen to pilots at high altitudes comprising the combination of a face mask and a tube on the outside of the mask adapted to be connected with a source of oxygen supply and provided with baffled openings for diffusion of oxygen in the vicinity of the wearer's mouth and nose, said mask being open under the nose and in front of the mouth of the wearer so that the external atmosphere may be breathed as 55 well as such oxygen as may be deflected through these openings and without interference with the wearer's speech.
